UNITED STATES PATENT OFFICE.

JULIUS PROEGER, OF UNIONTOWN, PENNSYLVANIA.

DESIGN FOR A GLASS VESSEL.

SPECIFICATION forming part of Design No. 20,079, dated August 5, 1890.

Application filed July 10, 1890. Serial No. 358,352. Term of patent 3½ years.

To all whom it may concern:

Be it known that I, JULIUS PROEGER, of Uniontown, in the county of Fayette and State of Pennsylvania, have invented a new and 5 original Design for Glass Vessels, of which the following is a full, clear, and exact description.

My invention relates to a design for glass vessels, such as vases, &c.; and it consists in 10 the design, substantially as hereinafter described and claimed, and as illustrated in the accompanying drawing, which shows in side elevation a glass vessel embodying my design.

The vessel is made in the form of a pipe

having a bowl A and a curved stem B extending therefrom. The vessel is figured with a pattern in relief, as shown in the drawing.

C is an ornamental suspending-chain.

I claim—

The design for glass vessels, substantially 20 as herein shown and described.

In testimony whereof I have hereunto set my hand this 7th day of July, A. D. 1890.

JULIUS PROEGER.
